LIQUID DISPENSING APPARATUS

Curtis F. Prangley, Evanston, Ill.

Application March 16, 1944, Serial No. 526,722

13 Claims. (Cl. 222—35)

1

This invention relates to liquid fuel pumps of the gasoline service station type, in particular to computer pumps which compute not only the volume of liquid dispensed but also the total cost thereof at any prevailing price per unit of volume.

Among the objects of the present invention are to provide in a liquid fuel dispensing system including a source of liquid supply a liquid displacement meter and a dispensing hose, computing and registering means actuated by a power source independent of the liquid supply system but controlled by the liquid displacement meter and, in turn, controlling the initiation of operation of the dispensing system; to provide in such a system an electrical follow-up mechanism or system controlled by the liquid displacement meter and operating the computing and registering means; to provide in such a system a novel and simplified computing and registering means; to provide computing and registering means which may be disposed remotely from the source of liquid supply, the liquid displacement meter and the dispensing hose, and to provide in such a system simple, automatic register resetting means.

Other and further objects will be apparent from the following specification when taken in connection with the accompanying drawings, wherein:

Figure 1 is a view in elevation with parts broken away, showing the application of the invention to a service station gasoline pump;

Figure 2 is a view in horizontal section taken substantially along the line 2—2 of Figure 1;

Figures 3 and 4 are fragmentary views in vertical section taken substantially along the lines 3—3 and 4—4 respectively of Figure 2;

Figure 5 is a diagrammatic view of a register means and includes a schematic diagram of the electrical connections;

Figure 6 is a diagrammatic view showing in section the motor drive of the cost registering means and its controls;

Figure 7 is a view similar to Figure 1 showing a modification of the pump;

Figure 8 is a view similar to Figure 1 showing a modification of the pump stand;

Figure 9 is a view in section taken on the line 9—9 of Figure 8;

Figures 10 and 11 are views showing a modified form of motor switch control means; and

Figure 12 is a view similar to Figure 5 showing a circuit embodying the control means of Figure 10.

The invention is shown, for purposes of illustration, and not by way of limitation, in connec-

2

tion with a modern type of dispensing device or service station pump.

Referring now to the drawing in detail, there is shown an underground tank 2 adapted to hold a quantity 4 of gasoline or other liquid to be dispensed. A pipe 6 of a dispensing line projects downwardly into the tank 2 and is provided at its lower end with the usual type of foot valve (not shown). The upper end of this pipe 6 projects into a casing or housing 8 which may be of any conventional type and connects with any usual type of pump 10 driven in the conventional manner by an electric motor 12. The pump discharges through a pipe 14 of the dispensing line into the air eliminator 16 of conventional structure and thence by means of pipe 20 of the dispensing line into a liquid displacement meter 22, from which the liquid passes through pipe 24 of the dispensing line. This meter may be of any general type and includes a meter shaft 26 which is rotated by means of the liquid flow through the meter, causing pistons or a wobble plate of the liquid displacement mechanism to turn the shaft 26 in accordance with the flow of liquid through the meter.

The pipe 24 may be connected at its upper end, which passes out of the housing 8, to any type of sight glass 28 and from the sight glass the liquid passes through the usual dispensing hose 30 and thence out through the nozzle 32 which is provided with a common nozzle valve 34. When not in use the nozzle and nozzle valve are supported on the conventional hose hook 36 carried by the housing 8 and overlie the outer end of the conventional lever 38 which through the usual rod 40 controls the usual motor switch 42 (schematically indicated in Figures 5 and 6), this switch being commonly termed "the nozzle switch" for it can be operated to closed position only when the nozzle is off the hook 36 and must be moved to open position before the nozzle is returned to the hook 36.

The switch rod 40 is provided with a latch member 44 (Figure 1) carried at the outer end of a bar spring or strip 46 fastened at its other end to the rod. This latch cooperates with a companion latch member 48 released by a solenoid 50 and urged into latching position by a spring 52 encircling the member 48 and bearing at one end against the fixedly mounted solenoid 50 and at the other end against a collar on the member 48. Both latch members 44 and 48 are preferably formed with beveled faces so that the latch member 44 may move over the member 48 when in projected position so that the switch rod 40 can be moved upwardly to move

the switch 42, even though the member 48 is in fully projected position. The member 48, as will hereinafter appear, serves to prevent closure of the motor circuit if the registering means is not reset between dispensing operations.

The meter shaft 26 drives directly or through any suitable gearing an alternating current Selsyn type generator or transmitter 54 and also, through suitable gearing, a direct current tachometer type generator 56. The alternating current Selsyn type transmitter 54 provides power for driving a volume register, indicated generally by the numeral 58, while the direct current tachometer type generator 56 serves as a speed control for the cost register, indicated generally by the numeral 60.

As shown more particularly in Figures 2 to 5, the volume register 58 comprises a film strip 62 wound on a supply roll 64 similar to the usual film supply roll common in motion picture apparatus, the roll 64 being detachably mounted on a drive shaft 66 in a manner as is conventional in such apparatus, and being fed from the roll 64 to a like take-up roll 68, also detachably mounted in the same manner on its drive shaft 70. The film 62 has printed on it, in any known manner, two sets or series of numerals or indicia 72 and 74 which represent the quantity or volume of liquid dispensed. It will be evident that each series of numerals may be composed of numbers running from zero to any convenient maximum amount in units, tens and fractions of gallons, and the numbers making up each series will be spaced longitudinally of the film.

The film in its passage from its supply roll 64 to the take-up roll 68 passes over suitable projection apparatus 76 which may comprise a film gate and supporting base 78 in a light box 80 having slots in its opposite edges to permit passage of the film therethrough. A projection source 82 comprising one or more projection lamps, which may be of relatively low power, is mounted in the bottom of the light box 80 in alignment with the picture or light aperture 84 of the film gate 78. From the aperture 84 the light passes through the film or through the numerals on the film to mirrors, prisms or other light reflecting means 86 and 88 by which the light rays are directed, through lens or other focusing means 90 and 92, onto translucent glass plates or translucent screens 94 and 96, the plate or screen 94 being set in a suitable holder on an escutcheon carried by one side wall of the housing 8 and covering a suitable opening in the housing. The screen or plate 96 is similarly mounted on the opposite wall of the housing and the mirrors or reflecting means 86 and 88 are relatively inclined oppositely at 45 degrees to the path of light from the projection source. One reflecting means is aligned vertically with that portion of the film on which one series of numbers is marked, while the other reflecting means is vertically aligned with the portion of the film on which the other series of numbers is marked. The numbers are, of course, formed on the strip in such manner that when reflected by the mirrors they will be in the usual upright position and in the proper order for direct reading on the translucent plates or screens 94 and 96.

It will be further evident that the translucent plates 94 and 96 need not be mounted in apertures in the housing but may be formed as plates mounted interiorly of the housing and

exposed through suitable transparent windows in the housing. A suitable shield (not shown) may be formed over the translucent plates to prevent the sun's rays from directly striking the plates, or there may be provided a short enclosing shield (not shown) around the glass plate for further excluding the direct rays of the sun at any time.

The film strip may be rendered opaque while the numerals are rendered transparent in any well-known manner or, conversely, the strip may be rendered transparent and the numerals opaque so as to secure the maximum contrast between the reproduction of the numerals on the screens and the remaining areas of the screens.

The film is provided with a control cut-out 98 so positioned as to engage a roller (not shown) or operating member of a "Micro" switch unit 100 of conventional structure embodying an operating lever 102 carrying a roller which is adapted to ride on the surface of the film and, when aligned with the control cut-out 98, to sink therethrough and operate the multiple switch plates of the "Micro" switch unit, so as to open the contacts 104 and 106 and close the contact 108. When the roller rides out of the control cut-out it lifts the operating member or lever 102 and closes the contacts 104 and 106 and opens the contact 108.

The shaft 66 and, consequently, the feed roll 64 are driven by an alternating current rewind motor 110 mounted in any suitable manner within the housing through a gear 112 on the motor shaft meshing with the gear 114 on the counter-shaft 116 carrying a gear 118 meshing with a gear 120 on a shaft 122 coupled to the shaft 66 by any suitable electrically operable clutch 124, such as, for example, a solenoid operated clutch of suitable conventional construction in which the clutch parts are engaged only when the actuating solenoid is energized and so long as the solenoid is deenergized the spring of the clutch holds the clutch parts in disengaged position.

The film take-up reel 68 is driven to feed the film in a reverse direction by means of an alternating current Selsyn motor or "receiver" 126 of conventional structure connected by the usual four-wire cable 128 to the alternating current Selsyn generator or transmitter 54, so that the shaft 130 of the motor is driven in exact synchronism with the shaft of the generator as it is rotated by the meter 22. The shaft 130 may be connected to the shaft 70 of the take-up roll 68 in any suitable manner, preferably by means of an intermittent motion mechanism or Geneva 132, of which the driver is connected to the shaft 130 and the driven part connected to a shaft 134 connected by any conventional one-way clutch, such as a roller clutch 136 to the shaft 70. The intermittent motion mechanism serves to advance the film step by step to position successive numbers over the aperture 84 in proper succession so as to integrate, in effect, the movements of the meter and thus indicate by the registering means successive predetermined increments of movement of the meter rather than instantaneous movements of the meter.

The cost register 60 is similar in construction to the volume register 58 and comprises a film 138 similar to the film 62 and similarly formed with two series of numerals 140 and 142 similarly arranged to indicate the cost of the liquid in dollars and cents. The film 138 is supplied from

a supply roll 144 detachably mounted on the drive shaft 146 and driven directly by the motor 110 through an electrically operable clutch 148 similar to the clutch 124.

It will be evident that the films may be fed from the supply rolls to the take-up rolls by feed sprockets in advance of the take-up rolls, with suitable loops between the sprockets and the take-up rolls, the sprocket and take-up roll for each film being geared to each for synchronous driving, as is usual in film projection apparatus.

The film is fed from the supply roll and passed over a picture gate or anvil, not shown but similar to the picture gate 78, by means of a take-up roll 150 detachably secured to a shaft 152. The take-up roll 150 is driven by an alternating current actuated, direct current speed controlled, induction motor, eddy current clutch 154 through an intermittent motion mechanism or Geneva movement 156 which is connected to the shaft 152 through a one-way clutch 158 similar to the clutch 136.

The film 138 is provided with a control cut-out 160 similar to the control cut-out 98 for similarly controlling the operation of a "Micro" switch unit 162 of the same structure as the "Micro" switch unit 100, and the unit 162 comprises a pair of normally open switches 164 and 166 and a normally closed switch 198.

The induction motor eddy clutch 154 comprises, as best seen in Figure 6, a housing 170 in both end walls of which is journaled the drive shaft 172. Two rotor parts 174 and 176 are journaled loosely on the shaft 172 for rotation relative thereto in opposite directions. The rotors 174 and 176 are each of the well-known short circuited rotor type. A cylindrical body or eddy current clutch member 178 is secured to the shaft between the rotors 174 and 176 and at its opposite ends projects into two annular slots in the inner faces of the rotors 174 and 176. The cylinder 178 is formed of copper, or other good electrically conducting material. The alternating current windings 180 and 182 are formed on the usual core members and positioned in proper alignment with their respective rotors. In a groove in the outer face of the rotor 174 there is inserted a direct current winding 184 to which current is fed through a supply cable 186 through the usual motor slip rings (not shown). A like direct current exciting winding 188 is inserted in a similar recess in the rotor 176 and this winding is similarly supplied with direct current through a supply cable 190. It will be evident that as a result of the eddy currents induced in copper cylinder 178 by the rotor 174 the cylinder will be impelled in one direction of rotation with a certain slip. Similarly by reason of the eddy currents induced in the cylinder by the other rotor 176 it will be impelled in the opposite direction with a certain slip. So long as the eddy currents induced in the currents from both rotors are equal, the cylinder will remain stationary and when one exceeds the other, the cylinder will be driven in a direction corresponding to the greater. Alternating current in proper phase relation is fed to the alternating current windings 180 and 182 through motor leads 192 and 194, connected to the alternating current supply leads L-1 and L-2 in one of which the nozzle switch 42 is inserted as shown in Figure 5.

Direct current is applied to the eddy clutch exciting winding 184 from the motor driven tachometer generator 56 which is connected to

the cable 186 through a cable 196 and an electrical price variator 198, which comprises a potentiometer 200 connected across the cable 196 and having its wiper arm connected to the cable 186. The wiper arm of the electrical price variator 198 may be connected in any desirable manner, as for example as illustrated in my co-pending application, Serial No. 496,421 filed July 28, 1943, now Patent 2,400,888, or my co-pending application, Serial No. 505,753 filed October 11, 1943, now Patent 2,428,382, to the price per gallon indicator 202 (Figure 1) mounted in the housing 8, and having suitable dials displayed behind a window in the housing.

Direct current for the eddy clutch exciting winding 188 may be supplied from the alternating current supply leads 192 and 194 through a half or full wave rectifier 204 of conventional structure and a potentiometer 206 connected across the outer terminals of the rectifier and to the cable 190, with the wiper of the potentiometer being connected to one of the wires of the cable 190. By adjustment of the potentiometer 206, the speed of operation of the eddy clutch 176 for minimum rate of dispensing may be calibrated and the rotation of this member so damped dynamically as to cause it to stop practically instantaneously in its forward rotation when the flow meter 22 stops, due to the closing of the nozzle valve. In fact, with the proper adjustment, the eddy clutch member 178 can be brought to a stop and reversed in either direction of rotation just slightly before the meter comes to a complete stop so that the driving of the cost register means ceases at the very instant the nozzle valve is closed even though there should be a slight lag between the closing of the nozzle valve and the stopping of the meter, which, of course, in conventional apparatus, causes a building up of pressure in the flexible dispensing hose but occasions no flow of liquid through the nozzle valve.

It should be noted that it is within the contemplation of this invention to employ an induction motor eddy current clutch having only one alternating current actuating winding, one rotor and one direct current eddy clutch exciting winding where the registering means or mechanism driven by the motor supplies a sufficient frictional or inertia load to bring the driven eddy clutch member 178 quickly to rest on a stopping of the meter 22.

As shown in Figure 5, the pump motor 12 is connected to the supply lines L-1 and L-2, on the load side of the nozzle switch 42, by the supply wires 208.

The film rewinding motor 110 is connected on one side to the supply line L-1 through wire 210 and on the other side to supply line L-2 through wire 212, a first contact 214 of a manually operable switch 216, wire 218, switch 166 of "Micro" switch unit 162 or switch 106 of "Micro" switch unit 100, and wired to supply line L-2 in advance of the nozzle switch 42 so that the circuit to the rewind motor may be completed when the nozzle switch 42 is open. It should be noted that the switch 166 of the "Micro" switch unit 162 and switch 106 of the "Micro" switch unit 100 are connected in parallel to the wires 218 and 220 so that the circuit to the rewind motor may be completed or maintained by either of these switches. The reset interlock control solenoid 50 is connected on one side to supply line L-1 as by wire 222 and on the other side through wire 224, switch 108 of "Micro" switch

unit 100, switch 168 of "Micro" switch unit 162, to wire 226 and then through wire 220 to supply line L-2 in advance of the nozzle switch 42 so that this solenoid may be energized when the nozzle switch is open.

The electrically operable clutch 148 is connected on one side by wire 228, the second switch contact 230 of the reset switch 216 and wire 232 to supply line L-1, and on its other side is connected through wire 234, switch 164 of "Micro" switch-unit 162, wire 236 and wire 220 to the supply line L-2. The electrically operable clutch 124 is similarly connected to the supply lines L-1 and L-2. On one side it is connected through wire 238, third switch 240 of reset switch 216, wire 242, and wire 232 to supply line L-1. On its other side this clutch is connected through wire 244, switch 104, of "Micro" switch unit 100, wire 246, and wires 236 and 220 to the supply line L-2. It should be noted that both of these electrically operable clutchies are connected to supply line L-2 in advance of the nozzle switch 42.

The operation of the invention in the form shown in Figures 1 to 6 is as follows: The master switch 248 for the supply line being closed to energize the entire equipment, when it is desired to dispense gasoline the nozzle is removed from the hook 36 and the switch lever 38 operated. If the registers are in zeroized position so that the lever-carried operating rollers and the "Micro" switch units are in the control cut-outs 98 and 160, then the several contacts of each "Micro" switch unit will be in the positions shown in Figure 5. The solenoid 50 will then be energized from the supply line L-1 through one blade of the master switch 248, the solenoid 50, the wire 224, the switches 108 and 168 in series, the wire 226 and the wire 220 to the supply line L-2.

It will be clear that if either one of the switches 108 or 168 is in open position by reason of the fact that its associated registering means is not in zeroized position, the solenoid will not be energized. When the solenoid is, however, energized, it withdraws the latch member 48 from the latch member 44 and allows movement of the switch lever 48 and switch rod 40 so as to close the nozzle switch 42. On closure of the nozzle switch 42, the pump driving motor 12 is energized through the circuit previously described. The pump 10 is thereby driven but, being of the conventional bypass type, merely bypasses the liquid from its high pressure side to its low pressure side until the nozzle valve 34 is opened. On opening of the nozzle valve 34, the meter 22 is driven by the liquid as it is dispensed. The consequent rotation of the meter shaft 26 effects rotation of the rotor of the Selsyn generator or transmitter 54 and of the tachometer generator 56. The tachometer generator supplies electric energy at a current or voltage proportionate to the speed of the meter shaft 26 and the proportion of this energy delivered to the exciting winding 184 of the induction motor eddy current clutch is determined by adjustment of the price variator 198 of which the potentiometer is calibrated in accordance with the price per unit of volume of the liquid dispensed, so that the proportion of energy delivered may be varied with the variations in price of the liquid.

The induction motor eddy current clutch, therefore, through the intermittent motion mechanism 155 and the one-way clutch 158 drives the film feeding or take-up roll 150 in predetermined speed ratio to the shaft 26. As the film

is thus fed, the cost numerals carried thereby are successively and progressively brought in line with the projection aperture in the picture gate and therethrough projected onto one of the screens or translucent plates 94 and 96 in opposite faces of the housing.

Through the alternating current Selsyn system comprising the transmitter 54 and the receiver 126, the film 62 of the volume registering means is driven in exact and unvarying positional synchronism with the meter shaft 26 so that the amount numerals on the film 62 are successively and progressively brought before the projection aperture 84 in the picture gate 78 and thus projected on the screens at opposite sides of the housing.

As the films 62 and 138 are moved by their respective feed rolls away from zeroized position, the lever carrying rollers of the "Micro" switch units 100 and 162 are lifted so that the switches 104 and 168 of the unit 100 and the switches 164 and 166 of the unit 162 are closed, while the switch 108 of the unit 100 and the switch 168 of the unit 162 are opened. The closing of the switches 104, 166, 164 and 166 effects partial completion of the circuits to the rewind motor 110, the electrically operable clutch 148 and the similar clutch 124. However, these circuits are not completed at this time since the manually operable reset switch 216 remains in open position.

The opening of the switches 108 and 168 results in the deenergization of the solenoid 50 so that the spring 52 projects the latch member 48 into the path of the spring carried latch member 44.

When a dispensing operation is completed by the closing of the nozzle valve, the meter 22 stops and, consequently, no further electrical energy is supplied to the exciting winding 184 of the induction motor eddy current clutch 154. The shaft driving clutch member 178 therefore stops, although the rotors 174 and 176 continue to rotate. Even if this clutch member, after stopping in its forward direction of rotation, reverses under the action of the rotor 176 and the exciting winding 184, this is without effect so far as the cost registering film is concerned, since in view of the one-way clutch 158, the shaft 152 can be driven by the motor only in one direction. It will be evident that the one-way clutch 158 may, if desired, be located between the intermittent motion mechanism and the motor 154 so that this mechanism will not be driven in a reverse direction if the clutch member 178 should be actually reversed in rotation in the interval between the closing of the nozzle valve and the opening of the nozzle switch 42.

Since the rotor of the transmitter 54 stops when the meter stops, the volume film 62 stops at the same instant.

When the nozzle is hung on the hook, the switch lever 38 is simultaneously operated to raise the switch rod 40 and the spring carried latch member 44 springs over the latch member 48 so that the switch rod 40 cannot be again operated until the registers have been reset.

To reset the registers, the reset switch 216 is manually operated to close its switch contacts 214, 230 and 240 which complete the energizing circuits for the rewind motor 110, the clutch 148 and the clutch 124 through the circuits previously described. The film supply rolls 64 and 144 are thus driven by the rewind motor in the opposite direction to wind the film on the rolls. During this reversing or resetting movement of the

films, the one-way clutches 136 and 158 permit free reverse turning of the take-up rolls 68 and 150.

It will be evident, of course, that the cost registering film 138 and the volume registering film 62 will not ordinarily be moved the same distance in the dispensing operation and, therefore, will not return to zeroized position at the same instant. Whichever film arrives first at the zeroized position will first cause operation of its "Micro" switch unit. The film 62 will ordinarily arrive at zeroized position first since its distance of movement in a reverse operation is generally less than that of the film 138. Assuming this to be the fact, the "Micro" switch 100 will be first operated to open its switches 104 and 106 and close its switch 108.

On opening of the switch 104, the clutch 124 will be deenergized and, therefore, its clutch parts disengaged so that rewinding of the film 62 will be instantaneously terminated. Opening of the switch 106 has no effect under these assumed conditions, for it is merely connected in parallel to the switch 166 which remains closed. The closing of the switch 108 partially closes the circuit of solenoid 50, which circuit, however, remains open at the switch 160. Thereafter when the film 138 reaches its zeroized position, its "Micro" switch unit 162 is operated to open the switches 164 and 166 and close the switch 160.

The opening of the switch 164 deenergizes the clutch 148 and the parts thereof then become disengaged. The opening of the switch 166 breaks the circuit to the rewind motor 110 and thus terminates the resetting operation. The manually operable reset switch 216 may now be released and its contacts thus spring to open position.

When the price per gallon of gasoline exceeds 10 cents, the film 138 must move a greater distance than the film 62. When the price of gasoline is 10 cents a gallon then the two films move equal distances. When the price of gasoline is less than 10 cents per gallon, the film 62 moves a greater distance than the film 138. Under normal circumstances in most locations, the price of gasoline does not drop to or below 10 cents a gallon and, therefore, the switch 106 of the "Micro" switch unit 100 may usually be eliminated for the film 62 will usually return to its zeroized position before the film 138.

In the modification shown in Figure 7, the alternating current Selsyn motor or receiver 126 may directly drive, through a shaft 250 coupled to the shaft of the receiver, the usual mechanical volume register 252, while the induction motor eddy current clutch 154, through a coupler shaft 254, drives the usual mechanical register 256. In this form, as in the form shown in Figures 1 to 6, the electrical price variator 198 is coupled electrically, in the same manner, to the direct current tachometer generator 56 and the speed controlled eddy current clutch exciting winding of the induction motor 154, while the adjusting means of this variator is coupled mechanically in the same manner to a unit price indicator 258.

In this form, as in the previous form, the induction motor 154 may be connected to the supply line in the same manner as illustrated in Figures 5 and 6.

In the form of the invention shown in Figure 8, the housing 8 is formed into two parts, one a lower part 260 and the second an upper part or turret 262 rotatably mounted on the lower part 260. The volume register 252, the cost register

256, the Selsyn receiver 126, the induction motor eddy current clutch 154, the unit price indicator 258 and the price variator 198 may all be mounted, in any conventional manner, in this turret 5 262. In this form, however, the registers 252 and 256 may each be a "single face register" rather than the "double face register," as in the form shown in Figure 7. These single face registers may be of the same structure as 10 the conventional double face registers, but with the one face of each register being eliminated.

The turret 262 may be provided with any suitable handle or lever means by which it can be turned manually by the attendant. Such means 15 may take the form of a ring 264 secured to the bottom of the turret 262. The electrical current from the alternating current Selsyn transmitter and the direct current tachometer 56 to the receiver 126 and the price variator 198, and from 20 the supply line to the induction motor 154 may be supplied through appropriate cables, including cable 128 from the transmitter 54, cable 196 from the generator 56 and a cable 266 from the supply line, which latter cable includes the wires 192 25 and 194. These cables pass upwardly through a pipe or suitable hollow fixture 268 fixed to and supported by a bracket 270 secured to the housing part 260.

An explosion-proof housing, which may 30 comprise a cylindrical depending wall 272 formed integrally with the bottom plate 274 of the turret, and a closure 276, may contain an inner drum 278 carried by the fixture 268, with the cables 128, 196 and 266 projecting into the drum through the 35 bottom wall thereof, and the wires thereof connected to the terminals 280 of resilient contact wipers 282 in number equal to the number of wires in the three cables. These wipers may project from the circumference of the drum 278 40 and each engages a companion slip ring 284 carried by an insulating sleeve 286 mounted in the explosion proof housing, concentrically with the drum 278, and rotatable about the drum as the turret rotates. These slip rings 284 may be connected by suitable terminal screws or other 45 fastenings to the wires of cables 288, 290 and 292 respectively, connecting the cables 128, 196 and 266 to the alternating current Selsyn receiver 126, the price variator 198 and the induction motor 154.

Thus it will be clear that the electrical connections, previously described, to the register driving motors and control means is maintained during the rotation of the turret and that accordingly the turret may be swung to any desired position to properly position the dials of the single face registering means for viewing by the purchaser and the attendant, and this regardless of the position in which the automobile 60 is driven up to the pump stand.

It will be further clear that inadvertent or intentional rotation of the turret during the dispensing operation will in nowise affect the accuracy of the registration.

65 In the form of the invention shown in Figures 10 to 12, the switch rod operated by the nozzle switch lever is formed in two parts, 294 and 296, joined by a lost motion connection 298 comprising, as illustrated, a sleeve 300 fixed to the part 70 294 and slidably receiving the enlarged end of the part 296. A spring 302 holds the parts normally in the position shown in Figure 10. When closure of the nozzle switch 42 is prevented by the latch member 48, the operation 75 of the lever 38, as on initiation of a dispensing

operation, causes the part 294 to move downwardly and the sleeve 300 to slide over the rod 296 against the action of the spring 302. In so doing, the sleeve engages and depresses the switch operating collar 304 against its spring 306. The rod 308 carried by the collar depresses the operating plunger of the "Micro" switch 310 mounted in a switch housing carried by the part 296. The switch 310 controls a circuit which includes a solenoid 312 of a solenoid operated reset switch 314 having switch contacts 316, 318 and 320 connected in the circuits of the rewind motor 110 and the clutches 148 and 124 in the same manner as the switch contacts 214, 230 and 240 of the reset switch 216. The solenoid is energized through a circuit which extends from the line L-1, through wire 210, wire 322, solenoid 312, switch 310, wire 218, switch 166 of switch unit 162 or switch 106 of switch unit 100 and wire 220 to supply line L-2. The solenoid 312 is thus energized to cause resetting of the registering means. On completion of the resetting, the solenoid is deenergized by the opening of the switches 166 and 106; the switch contacts 316, 318 and 320 then move to open position breaking the rewind motor circuits and further opening the circuits to the clutches 148 and 124.

Obviously the invention is not limited to the specific details of construction disclosed herein but is capable of other modifications and changes without departing from the spirit and scope of the appended claims.

I claim:

1. In a liquid fuel dispensing system, the combination of a flow line through which liquid fuel is adapted to flow under pressure, a liquid displacement meter in said line, a cost register, electric motor-clutch means driving said cost register, adjustable speed control means actuated by the meter and connected to said motor-clutch means for causing said clutch means to drive said cost register in proportion to the movements of the meter at ratios adjustable in accordance with the unit price of the liquid dispensed.

2. In a liquid fuel dispensing system, the combination of a flow line through which liquid fuel is adapted to flow under pressure, a liquid displacement meter in said line, a cost register, electrical driving means including an electrically operable eddy current clutch for driving said cost register, electrically operable and adjustable speed control means actuated by the meter and connected to said eddy current clutch means for causing said cost register to be driven by said driving means in proportion to the movements of the meter at ratios adjustable in accordance with changes in the unit price of the liquid dispensed.

3. In a liquid fuel dispensing system, the combination of a flow line through which liquid fuel is adapted to flow under pressure, a liquid displacement meter in said line, a cost register, a volume register, electrical driving means including an electrically operable clutch for driving said cost register, electrically operable and adjustable speed control means actuated by the meter and connected to said clutch for causing said cost register to be driven by said driving means in proportion to the movements of the meter at ratios adjustable in accordance with the changes in the unit price of the liquid dispensed, and an electrical follow-up comprising a position transmitter actuated by the meter, a position receiver electrically connected to said

transmitter and mechanically connected to said volume register for driving said register in positional synchronism with said meter.

4. In a liquid fuel dispensing system, the combination of a flow line through which liquid fuel is adapted to flow under pressure, a liquid displacement meter in said line, a cost register, a volume register, electrical driving means including an electrically operable clutch for driving said cost register, electrically operable and adjustable speed control means actuated by the meter and connected to said clutch for causing said cost register to be driven by said driving means in proportion to the movements of the meter at ratios adjustable in accordance with the changes in the unit price of the liquid dispensed, electrical driving means for the volume register, and electric power supplying means actuated by the meter and connected to said last mentioned driving means.

5. In a liquid fuel dispensing system, the combination of a flow line through which liquid fuel is adapted to flow under pressure, a liquid displacement meter in said line, a cost register, a volume register, electrical driving means including an electrically operable clutch for driving said cost register, electrically operable and adjustable speed control means actuated by the meter and connected to said clutch for causing said cost register to be driven by said driving means in proportion to the movements of the meter at ratios adjustable in accordance with the changes in the unit price of the liquid dispensed, and electrical driving means for the volume register, and means controlled by the meter for powering the same.

6. In a liquid fuel dispensing system, the combination of a flow line through which liquid fuel is adapted to flow under pressure, a liquid displacement meter in said line, a cost register, a volume register, electrical driving means including an electrically operable clutch for driving said cost register, adjustable speed control, electrically operable means actuated by the meter and connected to said clutch for causing said cost register to be driven by said driving means in proportion to the movements of the meter at ratios adjustable in accordance with the changes in the unit price of the liquid dispensed, and an electric follow-up drive for said volume register and actuated by the meter.

7. In a liquid fuel dispensing system, the combination of a flow line through which liquid fuel is adapted to flow under pressure, a liquid displacement meter in said line, a cost register, a volume register, electric motor means independent of the meter for driving the cost register, electrically operable speed control means actuated by the meter for varying the rate at which the cost register is driven by said motor to accord with the rate of movement of the meter, an electric motor for driving the volume register, electric power supply means for said motor and driven by the meter.

8. In a liquid fuel dispensing system, the combination of a flow line through which liquid fuel is adapted to flow under pressure, a liquid displacement meter in said line, a housing enclosing a portion of said dispensing line and said meter, a turret turnable with respect to said housing, registering means in said turret, electrically operable driving means for said registering means and mounted in said turret, electric power supply means in said housing, electric control means in said housing and actuated by the meter, and

means for connecting said power supply means and said electric control means in said housing to said electrically operable driving means in said turret, said connecting means including relatively rotatable contact members one secured to the housing and the other to said turret.

9. In liquid dispensing apparatus, a flow line, a meter in said line and operated by the flow of liquid therethrough, registering means comprising a roll of film marked with dispensing indicia, film projection means, a projection screen upon which said indicia is projected by said projection means from said film, film feeding means controlled by the meter, electrically operable means for re-winding said film on said supply roll to reset said registering means and electrically operable means controlled by the film for preventing flow of liquid through said line during rewinding of the film.

10. In liquid dispensing apparatus, a flow line, a dispensing valve in said line, a meter in said line and operated by the flow of liquid therethrough, registering means comprising a roll of film marked with dispensing indicia, film projection means, a projection screen upon which said indicia is projected by said projection means from said film, film feeding means controlled by the meter, electric motor means for re-winding said film on said supply roll to reset said registering means to zeroized position between successive dispensing operations of said valve, and automatic means operated by the film for rendering said re-winding means ineffective when said film reaches zeroized position.

11. In liquid dispensing apparatus, a source of liquid supply, a dispensing line connected to said source, a dispensing valve in said line, means for causing a flow of liquid through said line from said source upon the opening of the valve, a meter in said line and operated by the flow of liquid therethrough, registering means, means controlled by the meter for driving said registering means in proportion to the movements of the meter, an electric motor for driving said flow-causing means, said dispensing line including a flexible hose having a dispensing nozzle in which said valve is located, a support for said nozzle when not in use, means for initiating operation of said motor upon removal of the nozzle from said support, and electrically operable register resetting means operable upon removal of the nozzle from said support and controlling said motor initiating means to prevent operation of the motor until the registering means have been reset.

12. In a liquid dispensing apparatus, a flow line, a meter in said line and operated by the flow of liquid therethrough, registering means comprising two rolls of film, one of which is marked with volume indicia and the other with cost indicia, film projection means, a projection screen upon which the indicia on both said films

is simultaneously projected by said projection means from both said films, a follow-up comprising an electrical position transmitter driven by the meter and a position receiver driving the film containing the volume indicia, variable speed electric motor means for driving the film containing the cost indicia, electric generator means connected to the meter and to said motor means for controlling the speed of said motor means, an electrical price variator in the connection between said generator means and said motor means for adjusting the speed ratio between the motor means and the generator means in accordance with unit price of liquid to be dispensed, electric motor means common to both said films for rewinding said films, electric clutches, one for each of said films for individually connecting and disconnecting said rewinding motor means from the films, and a control associated with each film for rendering the clutch associated with that film effective to disconnect the rewinding motor from the film when the film on rewinding reaches zeroized position.

13. In a liquid dispensing apparatus, a dispensing line, a pump in said line causing a flow of liquid through said line, a meter in said line operated by the flow of liquid therethrough, an electric motor for driving said pump, registering means, means controlled by the meter for driving said registering means in proportion to the movements of the meter, said dispensing line including a flexible hose having a dispensing nozzle, a support for said nozzle when not in use, electrically operable register resetting means, means operable upon removal of the nozzle from said support for initiating operation of said register resetting means, and electrically operable means controlled by the registering means for automatically initiating operation of said motor when the registering means have been reset.

Certificate of Correction

Patent No. 2,511,006

June 13, 1950

CURTIS F. PRANGLEY

It is hereby certified that error appears in the printed specification of the above numbered patent requiring correction as follows:

Column 4, line 48, for "current" read *current*; column 12, lines 43 and 44, for "adjustable speed control, electrically operable" read *electrically operable and adjustable speed control*;

and that the said Letters Patent should be read as corrected above, so that the same may conform to the record of the case in the Patent Office.

Signed and sealed this 9th day of January, A. D. 1951.

[SEAL]

THOMAS F. MURPHY,
Assistant Commissioner of Patents.
